UNITED STATES PATENT OFFICE

FREDERICK REEVES BARRATT, OF KRUGERSDORP, TRANSVAAL, SOUTH AFRICA

TUBE-MILL SHELL LINER

Application filed January 5, 1925, Serial No. 686, and in South Africa March 11, 1924.

The present invention relates to liners for the shells of tube mills employed for grinding ores and like substances.

The invention also resides in the method of 5 grinding ores including a charge composed of large and small bodies which are of different relative weights so that when the charge is agitated the large bodies will be lifted and allowed to fall as a cascade on the 10 small bodies and at the same time constraining the charge so that the large bodies are directed in one direction and the small bodies in an opposite direction to consequently maintain an even distribution of the charge in the 15 tube mill.

The invention is illustrated in the accompanying drawings in which:

Fig. I is an interior view showing part 20 of a tube mill empty.

Fig. II is a cross sectional view illustrating the mill in operation.

Fig. III is a schematic view showing the mill cut longitudinally in half on A, B Fig. II and opened out on B.

25 2 is the shell of the mill. 3 indicates an end plate of the mill and 4 is the hollow trunnion through which the mill charge is fed into the mill. 5 (Fig. III) is a perforated plate through which comminuted material passes to the outlet trunnion 6.

The shell liner 7 is provided on its internal surface with ribs 8 which extend in the general direction of the length of the mill.

The purpose of the invention is to cause 35 said ribs to distribute the mill charge (indicated generally by 9) in a manner which improves the efficiency of the mill; and more particularly to convey the large and angular pieces 9^a of the mill charge from the inlet

40 end of the mill towards the outlet end and to convey the rather smaller and rounded pieces 9^b in the opposite direction, so as to keep the different sized constituents of the mill charge more evenly distributed along 45 the mill than is the case at present.

This object is attained by making the ribs 8 helical, with a long pitch, giving rise to a twist similar to the rifling of a gun as will appear from Fig. I.

The twist of the ribs is of the same hand 50 as that of the rotation of the mill, both viewed from the outlet end of the mill, as in Figs. I and II, in which arrow C indicates the direction of rotation.

The effect of this twist, provided the pitch 55 or inclination of the ribs and their cross section are somewhat as shown, is reflected in Figs. II and III. Fig. II shows the mill rotating whereby the mill charge is carried up on the rising side D of the mill and falls 60 over as a cascade which falls onto the pulp indicated by 10 and also impinges on the opposite side of the mill. The larger pieces 9^a of the charge tend to fall to the bottom 65 of the mass and into contact with the liner 65 in preference to the smaller pieces of the charge. The ribs tend to engage the pieces of the charge with which they are in contact and to carry them up on the rising side of the mill to a greater degree than the pieces 70 of the charge which are farther within the interior of the charge, and so out of immediate contact with the liner. Of the charge pieces which are in contact with them, the ribs tend to lift selectively the larger and 75 more angular fragments 9^a, so that the said larger and angular fragments are lifted to a greater extent than the fragments which have become reduced in size and somewhat rounded.

Such lifting however is far from positive 80 and the fragments, while being lifted, slip relatively to the liner in the direction of gravity, indicated by the arrow G in Fig. III. The inclination of the ribs causes this relative motion between the ribs and the fragments to have a component in the direction of the arrow E, that is towards the outlet 85 end of the mill; and as the larger and more angular pieces on the whole react more with 90

the liner than the other constituents of the charge, said larger and angular fragments are selectively propelled towards the outlet end of the mill.

5 Considering, on the other hand, the mill charge which falls through the pulp onto the liner on the descending side F of the mill, it will be noted that the inclination of the ribs at the point of the impact is, relatively 10 to gravity, opposite the inclination on the rising side. The falling fragments accordingly tend to glance off the ribs in the general direction (indicated by arrow H) of the inlet end of the mill; and so, on the whole, to 15 be transported towards that end of the mill. The charge which thus falls includes a higher percentage of partially reduced and rounded fragments than does the mill charge in contact with the liner on the rising side of 20 the mill, so that there is a tendency for such partially reduced and rounded fragments to be selectively transported towards the inlet end of the mill.

It is well known that in a tube mill charge 25 a preponderance of large and angular fragments is likely to be found at the inlet end of the mill and a preponderance of partially broken and rounded fragments towards the outlet end, with the result that comminution 30 of the ore proceeds more actively at the inlet end than towards the outlet end. The effect of selectively transporting the larger and angular pieces towards the outlet end and of 35 selectively transporting the less angular and somewhat reduced pieces in the opposite direction is to make the constitution of the mill charge more uniform throughout the length of the mill and so increase the grinding 40 capacity of the mill.

45 The pitch or inclination of the ribs is such that whilst performing the transporting functions above described, the ribs also function to a material extent as purely longitudinal ribs. That is to say they operate to a material extent to lift the charge on the 50 rising side D of the mill; and to act as an anvil, substantially transverse to the falling material on the opposite side F of the mill, as mentioned above. They also serve to agitate the charge by passing under and penetrating into the same as the mill rotates.

55 The inclination of the ribs moreover is such that they do not to any substantial extent form a transverse barrier which would tend to hinder free movement of the charge longitudinally of the mill such as naturally occurs by the spreading of the charge and the flow of comminuted pulp along the mill.

60 In practice satisfactory results have been obtained by so disposing the ribs that the angle between an imaginary line on the shell parallel with the axis of the mill and the rib ranges from a fraction of a degree up to about ten degrees. For grinding Witwatersrand ore in tube mills sixty-six inches in di-

ameter and twenty-two feet long, with a grinding charge consisting of large pieces of ore, the best results have been attained with an angle of about five degrees.

65 The cross-sectional shape of the ribs which gives the best results in the way of agitating the charge, whilst having a desirable lifting capacity, is that of a wave form.

70 The curvature of the wave form may differ on the opposite faces of the wave to promote 75 the two different functions which said faces are intended to perform. The functions of the rising face 11 being to lift, transport longitudinally and agitate the charge, it would as a rule have a somewhat steep rise 80 as appears from Figs. I and II. The reverse face 12 on the other hand functions chiefly as an anvil on which the mill charge falls on 85 the descending side of the mill and is thereby itself fractured as well as fracturing smaller pieces between itself and the liner. This face is consequently less steeply inclined so as to be approximately normal (in cross section) to the direction of the falling charge, 90 as seen in Fig. II.

95 The liner is conveniently built up of separate blocks as appears from Fig. I. A block comprises a base 13 of voussoir form shaped to fit the mill so that the blocks build up into an arch formation. The base is rectangular in plan, and the section of the rib which rises from the base is disposed thereto at the desired angle of the rifling and so that as the blocks are placed together in the intended formation, which usually involves 100 breaking joint, the sections of rib align to form a complete rib extending along the mill.

I claim:

1. The method of grinding ores including 105 a charge composed of large and small bodies of a weight less than the large bodies, agitating the charge to lift the large bodies so that they fall as a cascade on the small bodies, and simultaneously constraining the charge 110 so that the large bodies of the charge are directed in one direction and the small bodies in an opposite direction to consequently maintain an even distribution of the bodies of the charge.

115 2. In combination, a tube mill including a cylindrical shell, end plates, inlet and outlet trunnions connected with the respective end plates, a grinding charge comprising large bodies approximating to spherical form and smaller pebbles of less weight than the large grinding bodies, a liner for the interior of the shell having a plurality of substantially longitudinal ribs extending from one end of the shell to the other and disposed as a helix 120 of long pitch and of the same hand as the direction of rotation of the shell viewed from the outlet end thereof for agitating the charge during rotation to lift the large bodies 125 so that they fall as a cascade on the small 130

pebbles and simultaneously constrain the charge so that the large bodies are directed in one direction and the small pebbles in the opposite direction to consequently maintain an equal distribution of the charge, and the 5 inclination of the upper face of the cross-section of each rib on the rising side of the mill being greater than that of the opposite face, substantially as and for the purposes 10 set forth.

In testimony whereof I have hereunto set my hand.

FREDERICK REEVES BARRATT.
